UNITED STATES PATENT OFFICE.

WILLIAM N. WALKER, OF AKRON, NEW YORK.

POCKET-GUARD.

1,369,369.

Specification of Letters Patent. Patented Feb. 22, 1921.

Application filed July 31, 1919. Serial No. 314,396.

To all whom it may concern:

Be it known that I, WILLIAM N. WALKER, a citizen of the United States, residing at Akron, in the county of Erie and State of New York, have invented new and useful Improvements in Pocket-Guards, of which the following is a specification.

This invention relates to a pocket-guard or protector for trousers and other garments for preventing theft of a pocket book or other article without the detection of the wearer.

The object of the invention is the provision of a safety appliance of this character which, while affording the desired protection, permits the convenient insertion and removal of the wearer's hand when the guard is unlocked.

In the accompanying drawings:

Figure 1 is a fragmentary side view of a pair of trousers provided with the guard. Fig. 2 is a sectional side view thereof. Fig. 3 is a longitudinal section of the garment and the guard, showing the latter unlocked to admit the wearer's hand. Fig. 4 is a similar section showing the pocket closed and locked. Fig. 5 is a detached perspective view of the guard unlocked. Fig. 6 is a side elevation thereof, partly in section and locked. Fig. 7 is a horizontal section on line 7—7, Fig. 3, showing the swinging locking bolt folded out of the way.

Similar characters of reference indicate corresponding parts throughout the several views.

Referring to Figs. 1-7, the guard comprises a pair of opposing upright strips 1, and 2, 2^a, applied to opposite sides of the mouth of the pocket 3, preferably on its outer side, adjacent to the facing material 4 of the garment. These strips are constructed of suitable spring or flexible material, as steel or brass. The strip 1 located on the rear side of the pocket or that nearest the wearer may be continuous or formed in a single piece, while the outer strip is extensible and preferably composed of a pair of overlapping slidable strips 2, 2^a to permit of expansion of the strip to admit the hand of the wearer, or of its collapse or contraction with the pocket when the latter is to be locked. The upper and lower ends of this extensible strip are secured to the adjacent ends of the back strip 1 by rivets 5 or other suitable fastenings, which pen-

trate the pocket-fabric, as shown in Figs. 3 and 4. The lapped portions of the sectional strip 2, 2^a are united by an appropriate connection, preferably one or more pin-and-slot connections. In the construction shown, each section carries a headed pin 6 which slides in a longitudinal slot 7 in the other section, these two pairs of pins and slots being arranged on opposite sides of the center of the sectional strip.

Attached to the back strip 1 about midway of its ends is a locking bolt 8 adapted to pass through a pair of openings 9 in the strip sections 2, 2^a when the latter are in their contracted position in which said openings register, and also through a hole 10 in the facing-material 4, as shown in Fig. 4. The projecting outer end of this locking bolt is provided with an eye 11 adapted to receive any suitable means for retaining it in said openings, so as to securely lock the mouth of the pocket. The preferred retaining device shown in the drawings comprises a split eye or ring 12 engaging the eye 11 and composed of half-sections connected by a hinge 13 and each carrying one-half of a longitudinally-divided screw-shank 14 which engages a turn buckle 15. The opposite end of this buckle carries a swivel-eye 16 to which is linked a chain 17, the opposite end of which is permanently and reliably secured to the back-strip 1 or other part of the garment, adjacent to the entrance of the pocket, by which construction loss of said retaining eye is prevented. Any other suitable means may however be employed for this purpose.

In order to permit the bolt 8 to move out of the way when the wearer's hand is inserted in the pocket, the bolt may be pivoted to swing against the rear wall of the pocket, as shown in Fig. 7. In the construction there shown, the rear strip 1 carries a slotted bearing 18 which receives a transverse journal 19 of the bolt.

To lock the pocket, the same is closed by pressure against its outer side to contract the extensible strip 2, 2^a and bring the openings 9 of its sections into register. In this position, said openings and the hole 10 are passed over the unfolded bolt 8, after which the split-eye 13 is engaged with the eye of the bolt and locked by the turn buckle 15, thereby securely closing and locking the pocket and practically rendering it impos-

sible for a pick pocket to tamper with its contents without detection. To unlock the pocket, the acts just described are performed in the reverse order, and upon inserting the 5 hand in the pocket, the flexible and sectional front strip 2, 2^a bulges or expands with the adjacent pocket wall, admitting the hand without restraint and enabling a pocket book or other article to be conveniently inserted 10 or withdrawn.

While the construction herein described is the preferred one, I do not wish to be limited thereto, as the same may obviously be modified without departing from the invention 15 as covered by the appended claims.

While affording the desired protection, the device is easily applicable to the pockets of various garments.

By applying the guard to the outer side of 20 the pocket adjacent to its mouth, the greater part of the device is concealed and does not detract from the neatness of the garment, nor present parts or projections which are uncomfortable to the wearer's hand.

I claim as my invention:

1. A pocket guard, comprising a pair of opposing strips adapted to be applied to opposite sides of the pocket-mouth, one of said strips carrying a locking bolt, the other strip being composed of flexible sections secured 30 at their outer ends to the other of said strips and having their inner portions slidably connected and provided with openings arranged to receive said bolt in the contracted position of the sections.

2. A pocket guard, comprising a pair of opposing strips adapted to be applied to opposite sides of the pocket-mouth, one of said strips carrying a locking bolt, the other strip being composed of flexible sections secured 40 at their outer ends to the other of said strips and having their inner portions slidably mounted by a pin and slot connection, said slideable portions having openings arranged to register and receive said bolt in 45 the contracted position of the sections.

WILLIAM N. WALKER.
